UNITED STATES PATENT OFFICE.

GREEN TURNER, OF FORT SCREVEN, GEORGIA.

MINER'S LAMP.

1,371,823.

Specification of Letters Patent. Patented Mar. 15, 1921.

Application filed October 27, 1917. Serial No. 198,863.

To all whom it may concern:

Be it known that I, GREEN TURNER, a citizen of the United States, residing at Fort Scriven, in the county of Chatham and 5 State of Georgia, have invented certain new and useful Improvements in Miners' Lamps; and I do hereby declare the following to be a full, clear and exact description of the invention, such as will enable others skilled in 10 the art to which it appertains to make and use the same.

This invention relates to improvements in miners' or carbid lamps.

The object of this invention is to provide 15 a miner's lamp capable of being used by miners, thus obviating the necessity of the use of oil lamps, candles or the like articles and doing away with the use of matches.

20 A further object of the invention is to provide a carbid lamp, which is equipped with a water and a carbid chamber and a gas chamber interposed between the water and carbid chamber and means for permitting 25 the gas to be urged from the carbid chamber into the water chamber for forcing the water into the carbid for generating gas.

A still further object of this invention is 30 to provide a miner's lamp of this character, which will be simple, practical and comparatively inexpensive in construction and one that can be manufactured and sold at a low cost.

With these and other objects in view, the 35 invention consists in the novel combination and arrangement of parts hereinafter more fully described and claimed.

In the drawings:

Figure 1 is a side elevation of a miner's 40 lamp constructed in accordance with my invention.

Fig. 2 is a vertical sectional view of the same,

Fig. 3 is a transverse sectional view of the 45 same,

Fig. 4 is a detail sectional view of the gas pipe,

Fig. 5 is a detail sectional view of a gas outlet valve.

50 Referring to the drawings, the numeral 5 designates a lamp in its entirety and it comprises a cylindrical carbid receptacle 6, which is provided in its top wall with an opening, to the wall of which is secured an 55 annular flange 7, which is vertical in cross section and is provided with exterior screw-

threads. A water receptacle 8 comprises a cylindrical body 9, which is provided with interior screwthreads to facilitate the removable securing of the water receptacle to 60 the carbid receptacle through the medium of the flange 7. The upper end of the cylindrical body 9 flares outwardly to provide the water receptacle. The water receptacle 8 is provided intermediate its ends with a 65 partition 10, which defines a gas chamber 11 and water receptacle or compartment 12. A perforated baffle plate 13 is placed in the upper edge of the annular flange 7 and has secured on its upper side, a felt strip 14, 70 which is adapted to cleanse the gas passing from the carbid receptacle into the gas chamber 11.

A tube 15 is secured to the top wall of the water compartment 12 and extends downwardly through the partition 10 and terminates below the wall of the opening in the top wall of the carbid receptacle. The tube is provided adjacent the partition with an opening 16, which establishes a communication between the water compartment 12 and carbid receptacle. The lower end of the tube 15 converges as at 17 to provide a valve seat.

An operating rod 18 is slidably arranged 85 in the tube 15. The lower end of the rod 18 is substantially conical shape as at 19 to constitute a valve, which is normally seated on the valve seat 17 formed in the tube. The upper end of the operating rod is bent angularly as at 20 to provide an operating handle, and the rod 18 adjacent the handle is provided with screwthreads 21, adapted to be engaged by threads in the packing nut 22 to facilitate the movement of the valve end 90 of the lever upon rotation of the rod by the handle 20, thus it can be seen that the valve 19 may be unseated to permit the water from the water compartment 12 to run down through the tube into the carbid receptacle 100 6 and generate gas, which will pass up through the baffle plate 13 through the felt strip 14 into the gas chamber and be thoroughly cleansed during its passage.

A burner 23 is secured to the cylindrical 105 body 9 and communicates with the gas chamber. The outer end of the burner is extended laterally therefrom and is surrounded by a reflector 24.

An ignition means 25 is secured to the reflector 24 and is located directly under the end of the burner 23, whereby the gas pass-

ing through the burner 23 may be ignited by the sparks from the ignition device 25 when it is desired to use the lamp.

The top wall of the water compartment 12 is provided with an opening in which is removably secured, a plug 26, which has interposed between itself and the wall of the compartment, a rubber gasket 27, which causes a water tight joint therebetween.

10 The plug 26 is adapted to be removed to facilitate the filling of the compartment 12 with water. It is to be understood that the baffle plate 13 is removably fitted in the upper end of the flange 7 so as to facilitate its removal to permit the carbide receptacle 6 to be filled with carbide.

15 A gas pipe 28 has one end secured to the top wall of the water compartment 12 and communicates therewith. The other terminal of the gas pipe 28 is secured to and communicates with the gas chamber 11 through the wall of the body 9. A valve 29 is arranged in the pipe 28 adjacent one end thereof to facilitate the closing of the communication between the water compartment and gas chamber. The inner end of the pipe, which is located in the water compartment has secured thereto, a felt strip 30, which prevents the water from passing up through and into the pipe.

20 The pipe 28 is provided with an opening 29' which is covered by a suitable valve 30', which valve is normally held seated by a spring arm 31' having one end secured to the pipe as at 32'. An adjusting screw 33' is secured to the pipe as at 34' and co-operates with the spring arm 31' to permit the valve to be regulated so as to permit the valve to be unseated upon increased pressure within the tank or pipe, thus avoiding explosion by the accumulation of too much gas.

25 In operation, the gas generating in the gas chamber is let into the water chamber through the medium of the valve 29, which is adapted to be open, thus the water will be under pressure and upon the unseating of the valve 19 from its seat 17, the water will be forced into the carbide receptacle 6 through the tube 15 and the mixing of the carbide and water will generate gas, which will pass up through the baffle plate 13 and felt strip 14 and terminate into the gas

chamber 9 from where it can pass out through the burner 23 and be ignited 55 through the ignition device 25, it being understood that it is only necessary to seat the valve 19, cutting off the supply of water to the carbide receptacle, thus stopping the generation of gas when the lamp is not to be 60 used.

The bracket 31 is secured to the exterior of the water compartment 12 and has its opposite ends curved outwardly and inwardly to facilitate the attaching of the lamp to a 65 miner's cap or the like.

What is claimed is:

1. A portable acetylene generator and lamp having superposed water and carbide chambers and an interposed gas chamber, 70 from the latter of which extends a burner tube, and between which and the carbide chamber is located a gas straining medium, a water feed pipe connecting the water and carbide chambers and controlled by an exteriorly accessible valve mechanism, and a valved pressure pipe disposed exteriorly of and connecting the gas and water chambers and constituting a handle by which the lamp may be manipulated. 80

2. A portable acetylene generator and lamp having superposed water and carbide chambers and an interposed gas chamber, from the latter of which extends a burner tube, and between which and the carbide 85 chamber is located a gas straining medium, consisting of a perforated baffle plate and a superposed felt web arranged in parallelism therewith, a water feed pipe connecting the water and carbide chambers and extending axially through the same and the interposed gas chamber, said water feed pipe being provided with a controlling valve having an operating means disposed exteriorly of the said chambers and at the upper end of the feed tube, and a valved pressure pipe disposed exteriorly of and connecting the gas and water chambers and designed to equalize the pressure above and below the contents of the latter. 90

In testimony whereof I affix my signature in presence of two witnesses.

GREEN TURNER.
